UNITED STATES PATENT OFFICE.

HANS HENRIK SCHOU, OF COPENHAGEN, DENMARK, ASSIGNOR TO FLAKES A/S, OF COPENHAGEN, DENMARK.

EMULSIFYING APPARATUS.

1,254,734.

Specification of Letters Patent. Patented Jan. 29, 1918.

Application filed July 12, 1916. Serial No. 108,958.

To all whom it may concern:

Be it known that I, HANS HENRIK SCHOU, a subject of the King of Denmark, residing at Pilealle No. 27, Copenhagen, in the Kingdom of Denmark, have invented certain new and useful Improvements in Emulsifying Apparatus, of which the following is a specification.

This invention relates to the construction 10 of the casings of emulsifying apparatus of the type in which a rotating emulsifying disk is inclosed between the two sides or members of the casing, the surfaces of the disk and casing approaching each other very 15 closely so as to form narrow emulsifying channels through which the ingredients of the emulsion pass during the rotation of the disk at high speed. Such apparatus forms the subject matter of Letters Patent 1192492 20 issued to S. H. Blichfeldt and the present invention is more particularly directed to the improvement of the apparatus described in the above specification, in which apparatus as originally proposed the two sides of 25 the disk casing are secured together by bolts which provide for adjustment of the emulsifying channels by compression of packing placed between the two casing members. The chief objects of the present invention 30 are to improve the method of adjusting the width of the emulsifying channels and to facilitate the opening and closing of the disk casing.

It is essential that the adjustment should 35 be made with the greatest possible accuracy and it is found that adjustment by means of bolts is very complicated and takes considerable time while the accuracy obtainable, either with regard to the width of the emulsifying channels or, what is even more important, to the parallelism of the surfaces 40 of the channel, is not sufficiently exact for full efficiency of the apparatus. In the improved construction the two disk shaped members of the casing, which receive between them the emulsifying disk, are connected together by an interrupted screw, one of the said members being mounted so as to swing into open or closed position and to

turn through an angle when closed, to cause 50 the engagement of the interrupted screw threads. The adjustment of the emulsifying channel is effected by turning the movable casing member through any predetermined angle after engagement with the 55 fixed member, and the members are secured in the correct relative position after adjustment by a pneumatic ring set in a channel in one of the said members and inflated through a suitable valve, so as to bind 60 against the face of the second member and by varying the inflation pressure to give a final fine adjustment to the emulsifying channels. This ring serves both to form a liquid tight seal and to prevent any rotation 65 of the movable casing member after adjustment.

In order that the said invention may be clearly understood and readily carried into effect, the same will now be described more 70 fully with reference to the accompanying drawings, in which:

Figure 1 is a section through the axis of an emulsifying apparatus embodying this invention.

Fig. 2 is an end elevation and Fig. 3 a plan of the apparatus.

A is the fixed member of the disk shaped casing, the boss *a* of which is provided with the bushing *a'* forming a bearing for the 80 shaft of the emulsifying disk (which is not shown in the drawings) and with the lubricating ring *a''* for the said shaft. B is the second disk member mounted to turn in the ring *c* of the jointed carrier C pivoted in 85 the brackets *a''* on the back of the casing member A. D is the pneumatic ring which forms a liquid tight joint between the members A and B.

The two casing members are connected together by the interrupted screw threads *a''* and *b* which are of buttress type as shown in Fig. 1 (that is, the generating lines of the buttress faces are perpendicular to the axis of the apparatus) to give accuracy of adjustment, the screw thread *a''* being on the periphery of the member A while the thread *b* is on the inner face of the over-

5 hanging flange b' which encircles the fixed member A. As shown in Fig. 2 the thread segments a^4 and b are of unequal length, the segments a^4 being considerably longer than the segments b , the range of adjustment, which depends upon the length of the longer segments, being therefore increased as compared with segments of equal length.

The operation of the casing is as follows:—

When open the casing member B is swung back on the jointed carrier C after the manner of the breech member of a gun, leaving the cavity E, in which the emulsifying disk lies, quite open. To close the casing the member B is swung over the fixed member A, the gaps between the screw segments a^4 and b allowing the flange b' to encircle the member A. The pneumatic ring D is in deflated condition and the member B is free to turn in the ring c to cause the threads a^4 and b to engage. The member B may be turned by handles b^2 and the adjustment is made until the narrow gap e between the adjacent faces of the members A and B is reduced to the desired width, giving the proper dimensions to the emulsifying or homogenizing channels formed between the faces a^5 and b^3 of the members A and B and an emulsifying disk such as is indicated diagrammatically in chain lines at F. The faces a^5 and b^3 are shown narrow, so as to inclose only a small annulus of the disk, but they may be of any required depth according to the extent of emulsifying surface desired. The ingredients pass from the middle to the periphery of the casing, escaping through the outlet a^6 in the member A.

40 The method of introducing the liquid into
the emulsifying apparatus forms no part
of the present invention but as this is more
especially intended as a constructional im-
provement on the machine described in the
specification of Patent No. 1192492 already
45 referred to the method of introducing the
ingredients described in that specification
can be employed in the present case, the oily
ingredient being intermittently admitted to
the cavity E through the passage f, g, by
50 means of the rotating supply tube h having
the perforations i registering with the pas-
sages f, g. The tube h is driven from the
shaft k by the worm l, the device being car-
ried by the casing extension m. The watery
55 ingredient is admitted continuously to the
cavity E through the passage n.

When the proper adjustment of the member B has been made, according for example to suitable markings on the two members indicating the width of the emulsifying channel obtained, the ring D is inflated through a valve at d (Fig. 2) and the buttress faces of the thread segments a^4 and b are tightly pressed together, the ring simultaneously

binding the casing members to prevent displacement and forming a liquid tight joint between them. As the ring D expands under pressure equally at all parts the pressure exerted on the two disks is equal throughout the whole circumference and the parallelism of the surfaces a^5 , b^3 is thus insured, the buttress formation of the threads a^4 , b forming a further guarantee against any obliquity in screwing up the casing members. It is found in practice that a variation in the compression of the air in the tube or ring D makes a very slight difference in the width of the emulsifying channels and owing to the extreme narrowness of these channels the fine adjustment thus obtainable is of great importance. The screw action permits of an adjustment within intervals of 0.002 mm. or less and the variable inflation of the ring permits of a considerably finer adjustment which can of course be effected without interrupting the working of the emulsifier. To open the casing the ring D is first deflated and the member B then turned until the screw segments a^4 and b are free, whereupon the member B can be swung back clear of the fixed member A.

What I claim and desire to secure by Letters Patent of the United States is:—

1. In a disk emulsifier, a disk casing comprising two disk members, means for securing the two members together and an inflatable ring located between the said members. 95

2. In a disk emulsifier, a disk casing comprising two disk members, a screw connection for securing the two members together and an inflatable ring located between the said members. 100

3. In a disk emulsifier, a disk casing comprising two coöperating disk members and interrupted male and female screw threads on the said members adapted to engage and secure the members adjustably together. 105

4. In a disk emulsifier, a disk casing comprising two coöperating disk members and interrupted male and female screw threads of buttress type on the said members adapted to engage and secure the members adjustably together. 110

5. In a disk emulsifier, a disk casing comprising two coöperating disk members of which one is fixed while the other is pivotally mounted on the fixed member so as to swing outwardly to open the casing, an overhanging flange on one of the said members having an interrupted female screw thread and a coöperating interrupted male screw thread on the periphery of the second member. 115 120

6. In a disk emulsifier, a disk casing comprising two co-operating disk members, interrupted male and female screw threads on the said members adapted to engage and se- 126

cure the members adjustably together and an inflatable ring located between the two members in an annular groove.

7. In a disk emulsifier, a disk casing comprising two coöperating disk members of which one is fixed and the other movable, a jointed carrier on the fixed member having

at its outer end a supporting ring in which the movable member is mounted to turn on its axis, and male and female interrupted screw threads on the said members, by which they are adjustably secured together on closing the casing.

HANS HENRIK SCHOU.
